SIGNAL DEVICE AND MECHANICAL
MOVEMENT

Frank S. Nawrocki, North Hollywood, Calif.

Application September 26, 1933, Serial No. 691,033

9 Claims. (Cl. 116—43)

This invention relates to a signal device and mechanical movement for operating the same. The signal device is more particularly intended for automobile traffic signaling but the invention is not limited to signals of such a character.

With regard to the mechanical movement included in the invention, said mechanical movement may be adapted to various other uses than the operation of a signal element.

10. The signal provided by this invention is adapted for attachment to various makes of self-propelled vehicles now on the market, in a position wherein it is easily operable by the driver.

The signal device provided by this invention, 15 although primarily intended to be operated automatically by the steering mechanism of the vehicle is nevertheless of such a construction that if desired it may be arranged for direct manual operation by the driver.

20. Other objects, advantages and features of the invention may hereinafter appear.

Referring to the accompanying drawing which illustrates what is at present deemed to be a preferred embodiment of the invention.

25. Fig. 1 is a face view of the device displaying a go signal.

Fig. 2 is a vertical section on line 2—2 of Fig. 3.

Fig. 3 is a transverse section on line 3—3 of Fig. 2.

30. Fig. 4 is a vertical section on line 4—4 of Fig. 2, portions of the structure being broken away to contract the view.

Fig. 5 is a side elevation showing sufficient structure to illustrate the application of the invention to a self-propelled vehicle.

Referring in detail to the drawing and describing first the parts which embody the mechanical movement for operating the signal proper, the housing 11 is preferably of a sheet metal character. It is shown in the drawing as of a parabolic shape as seen in vertical mid-section. Said housing is completed in front by means of a glass cover 12 behind which is a face plate 13 having therein a transversely elongated sight opening 13x through which is displayed a signal element having a general designation 14. Said housing is supported in any suitable manner as by means of a standard 15 having a head flange 16 to which the lower side of the housing is riveted.

50. Within said housing is mounted a supporting member or bracket plate having side arms 17 which are spaced apart from each other to include between them the operating parts hereinafter described. Each of said arms 17 has at one 55 end an expanded portion 18 whereby it is secured

to the face plate 13 and at its other end an inwardly directed portion, these inwardly directed portions combining to form the bridge member 19. Said bridge member 19 has identically shaped upper and lower side plates 20 which are spaced apart from each other to form an inside housing. This inside housing is provided with a backwardly directed reduced open end portion or extension 21.

Each side of the housing extension 21 is provided with a pivot pin 25 and upon these pivot pins is rockably mounted a segmental member 26 which has end arms 27 to cooperate with said pins. Said segmental member 26 is provided at each end with an ear 28 or 29, said ears being respectively connected with operating rods 30 15 and 31. These operating rods are in turn connected with a pivotally supported operating member 32 having an operating arm 33. A rod 34 is shown connected at its upper end to said arm 33 and at its lower end to the bell crank 35 20 which, in turn, is actuated by a rod 36 connectable with any suitable operating means located more rearwardly on the vehicle.

Returning to the signal operating means shown in Figs. 2, 3 and 4, the segmental member 26 is 25 provided with a spiral slot 45 through which extends a pin 46 which is carried by the closed end portion of a yoke member 47 pivoted at 49. Said yoke member has at each side an arm 48. The pair of arms thus provided embrace the inner 30 housing formed by the plates 20 and the housing extension 21 carried by them. Within the space bounded by these parts 20 and 21 is mounted an inner yoke member 50 which cooperates with the yoke 47. The connecting means between these 35 two yoke members is a tension spring 51, one end of said spring being secured to a lug 52 which projects inwardly from the closed end portion of the yoke 47. The other end of said spring is secured to a lug 53 which projects inwardly from 40 the closed end portion of the yoke 50. The extremities of the arms of the yoke 50 are each pivoted to the housing at 54, and the opposite end of the yoke 50 is provided with an operating arm 55. Said operating arm 55 projects through 45 a spiral slot 56 with which the signal-carrying cylinder 57 is provided. The cylinder 57 is fixed to an axial shaft 58, the extremities of said shaft being journaled in the arms 17. This construction provides means whereby the oscillatory 50 movements of the yoke 50 together with its arm 55 cause the signal-carrying cylinder 57 to rock about its axis.

The cylinder 57 is provided with radial arm 59 whereby there is secured thereto a multiple sig- 55

nal plate 60. Said signal plate, as shown in Figs. 1 and 2, is provided with a—go—indicating section 61, and an indicating section 62 which may be used as a stop signal, the portion 63, located 5 between the other two sections thereof, forming a connection between them. Said plate may be formed as a segment of a polygonal tube, as shown in the drawing or it may be uniformly curved, if preferred. The length, shape and position of the spiral slot 56 of the cylinder 57, is such as to cause the arm 55 at one limit of its travel to display the "go" indicating signal and at the other limit of its travel to display a stop indicating signal.

15 These signals will be rendered more clearly visible by the electric lamps 66 mounted within the main casing 11.

20 The invention is not limited to the use of yoke-shaped levers but levers may be arranged within the scope of the appended claims of a different character providing that they are oppositely pivoted to supporting means and have their free 25 end portions connected to each other by an overthrow spring.

25 It will be seen that the overthrow spring 51 connects the free end portions of the two cooperating yoke-shaped levers and that the swinging movements of each of said levers describe figures shaped as sectors of cylinders the upper and 30 lower sides of which are bounded by parallel planes, the apex of each of said figures being directed towards the arc of the other, said levers swinging in an overlapping relation to each other. A space economizing structure is thereby 35 produced.

The operation through the rearwardly operable rod 36, will be carried out by reason of the fact that the rocking of the segmental member 26 will cause its spiral slot 45 to act upon the arm 46 of the yoke 47 and said yoke through the spring 51 will act upon the inner yoke 50 which in turn through its arm 55, which engages the slot 56 of the signal-carrying cylinder 57, will turn said member 57 to the desired extent.

40 In the performance of the operation which has been described, the spring 51 which connects together the yoke shaped levers will act as an overthrow spring and shortly after the outside lever 47 passes its central position said spring will 45 cause the inside lever 50 to begin to move, and as soon as the latter lever starts moving the spring will quickly complete its swing thus causing the signal element proper to move in a quick and efficient manner.

45 I claim:

1. In a device of the kind described, a cylindrical member having a spiral slot, means to turnably support said member, a signal proper, connecting means between said member and signal proper whereby the latter is movable to and from display position by turning movements of said member, a part operatively engaging said slot, and means to reciprocate said part lengthwise of said member in order to impart reverse turning movements thereto.

2. A signal operating device comprising two turnable or rocking members each of which is provided with a segmental portion having a spiral slot therein, one of said members being a 50 driving member and the other being a driven member, means to mount said members to turn or rock about parallel axes, a driving lever pivotally supported at one end and having its free end projecting through the slot of the driving segment to be reciprocated thereby, a driven lever

5 pivotally mounted at one end and having its other end projecting through the slot of said driven segment, and a spring connection between said levers to cause the operation of the driving lever to actuate the driven lever.

3. A signal operating device comprising a housing having open ends, a yoke shaped driving lever external to said housing having its limbs pivotally secured to one end portion thereof, an arm projecting from the closed end of said lever, a 10 segmental member rockably mounted upon said housing and having a spiral slot through which said arm projects in order that the rocking of said member may in turn rock said lever, a yoke-shaped driven lever within said housing having 15 its open end pivotally secured to said housing and directed toward the closed end of said driving lever, a tension spring connecting together the closed end portions of said levers in such a manner that the rocking of one of said levers rocks 20 the other lever also, an arm projecting from the closed end portion of the driven lever, and a rocking member having a segmental portion provided with a spiral slot into which said last recited arm projects to rock said member.

4. A mechanical movement comprising two members of a curved character each having a slotted segmental portion, supporting means to mount said members in such a position that they are rockable about parallel axes, a part 25 mounted upon said supporting means and engaging the slot of one of said members in order that the oscillation of said member may move said part back and forth, another part movably mounted upon said supporting means and engaging 30 the slot of the other member, and means operatively connecting said two parts to cause the oscillation of one of said members to oscillate the other also.

5. In a mechanical movement, a support, two 40 levers mounted upon said support adjacent to each other, each of said levers comprising two limbs which are united to each other at one end, means to pivotally connect to said support the ends of said limbs farthest from their point 45 of union with each other, a tension spring connecting the united portions of the limbs of one of said levers to the corresponding part of the other of said levers, means to oscillate one of 50 said levers, the other of said levers being positioned to be oscillated back and forth across dead center by said spring, and power transmitting means connected with the last mentioned lever.

6. In a signal device, a cylindrical member having a spiral slot in its wall, a support whereon 55 said member is rockably mounted, a lever having one of its ends pivotally mounted upon said support, the free end of said lever projecting into said slot in order that the oscillation of said lever may also oscillate said cylinder, another lever 60 pivotally mounted upon said support in a superposed relation to the first lever, the free ends of said levers being directed in opposite directions, a spring operatively connecting the free end of one lever with the corresponding end of the 65 other lever, and means to oscillate the second mentioned lever thereby, through said spring, transmitting oscillatory movements to the lever which actuates said cylinder.

7. In a mechanical movement, a support, two 70 yoke shaped levers mounted upon said support, each of said levers having arms which extend in substantial parallelism to each other and are pivotally secured to said support at the open end of the yoke, said yokes having their open ends di- 75

rected oppositely to each other, an overthrow tension spring securing together the closed end portions of said yokes to cause one of said yokes to operate the other when a movement across 5 dead center has occurred, and means to operate one of said yoke-shaped levers to impart a quick overthrow movement to the other of said yoke-shaped levers.

8. In a mechanical movement, a support, two 10 yoke shaped levers mounted upon said support, each of said levers having arms which extend in substantial parallelism to each other and are pivotally secured to said support at the open end of the yoke, one of said levers swinging between 15 the arms of the other, said yokes having their open ends directed oppositely to each other, an overthrow tension spring located between the arms of both of said levers and securing together the closed end portions of said yokes to cause 20 one of said yokes to operate the other when a movement across dead center has occurred, and means to operate one of said yoke-shaped levers

to impart a quick overthrow movement to the other of said yoke-shaped levers.

9. In a mechanical movement, supporting means, two cooperating swingable levers mounted thereon, said levers each having one end pivoted to said means, said levers being mounted adjacent to each other, an overthrow tension spring which connects the free end portions of 5 said levers, the swinging movements of each of said levers describing a figure shaped as a sector 10 of a cylinder, the upper and lower sides of which are bounded by parallel planes, the apex of each of said figures being directed towards the arc of the other, means to swing one of said levers across 15 its dead center in an overlapping relation to the other, and power transmitting means connected to the other of said levers, said levers each swinging upon an axis intersecting the sector-shaped figure described by the swinging of the other lever. 20
